COVERED CONTAINER

Kenneth T. Butter, Kalamazoo, Mich., assignor
to Sutherland Paper Company, Kalamazoo,
Mich., a corporation of Michigan

Application April 16, 1947, Serial No. 741,853

7 Claims. (Cl. 229—36)

1

This invention relates to improvements in covered containers.

The main objects of this invention are:

First, to provide a lined covered container which may be shipped or stored in the knockdown and quickly and easily set up for use with the liner effectively enclosing the contents, the liner being desirably of moisture resisting material.

Second, to provide a covered container which may be quickly set up to receive the contents and the cover closed.

Third, to provide a container having these advantages which may be very economically produced and shipped and stored in the knockdown or flat.

Objects relating to details and economies of the invention will definitely appear from the description to follow. The invention is defined in the claims.

A container which embodies the features of the invention is clearly illustrated in the accompanying drawing, in which:

Fig. 1 is a front perspective view of a structure embodying the invention with the cover closed.

Fig. 2 is a front perspective view with the body of the box erected to receive contents and with the cover in upright position.

Fig. 3 is an end elevation showing the erected box with the cover partly closed.

Fig. 4 is an end elevation of the closed container.

Fig. 5 is a plan view of the container in the knockdown or extended form with the liner partially broken away.

The container of this invention comprises a bottom 1, front body wall 2, rear body wall 3 and end body walls 4, these walls being hingedly connected to the bottom by the hinging scores conventionally shown at 5. The front wall 2 is provided with corner flaps 6 hingedly connected thereto at 7, the corner flaps having extensions 8 hingedly connected to their upper edges at 9. The rear wall is provided with corner flaps 10 hingedly connected thereto by the scores 11. The front wall has a top flap 12 hingedly connected thereto at 13 and has a longitudinal slit 14 with upwardly diverging extensions 15 providing a deflectable portion 16. The corner flaps have upwardly projecting tongues 17 on their end edges. The end walls have slits 18 extending diagonally from their bottom edges, these slits having angled extensions 19 at the ends thereof. The slits provide deflectable end wall 55

2

portions 20. When the box is erected the corner flaps are inserted through the slits and their tongues 17 are engaged with the portions of the end walls above the slits.

The cover 21 is hingedly connected to the upper edge of the rear wall 3 at 22 and is provided with end flaps 23 hingedly connected thereto at 24 and with a closure flap 25 hingedly connected thereto at 26. The closure flap has a tongue 27 which can be snapped into engagement with the front wall through the slit 14, the deflectable portion 16 permitting this engagement by merely pressing on the cover closure flap. The cover end flaps 23 have front and rear extensions 28 and 29 which are disposed through the slits 18 when the cover is completely closed. The extensions 29 have tongues 30 which engage the edges of the front slits of the body end walls, thus locking the cover in closed position.

These parts are all formed of an integral blank or sheet of container stock scored to provide the hinging connection and suitably cut and slit to provide the parts designed to perform the functions stated.

The liner 31 is in the form of a sheet, desirably of transparent moisture or water resisting material. This sheet is of a width substantially that of the blank and is disposed with one end substantially flush with the end edges of the front corner flap extensions 8. The other end of the sheet terminates near the outer or swinging end of the cover. Desirably the sheet is adhesively secured to the container blank by a strip of adhesive 32 disposed along the upper edge of the front wall and extending on to the front corner flaps. It is desirably secured to the rear wall by a strip of adhesive 33 disposed adjacent the upper edge of the rear wall and extended on to the rear corner flaps 10. The other end of the sheet is secured by a strip of adhesive 34 to the inner side of the cover only.

With the liner thus secured it is easily positioned when the box is erected. In Fig. 2 the box is shown in erected position to receive the contents with the corner flap extensions 8 partially swung inwardly. These extensions engaging the liner sheet serve to tuck or fold the corner portions of the front end thereof inwardly and not only serve as supports for the liner sheet but in effect as finger pieces which may be used to properly fold the liner upon the contents. After these parts are folded inwardly, or beginning with the position shown in Fig. 2, the front edge of the liner may be folded inwardly so that the

cover can be folded down over the contents and the cover flap extensions 28 and 29 engaged with the slits in the end walls over the front and rear wall corner flaps, the tongues 30 engaging to retain the cover in closed position. The front wall top flap 12 is folded down desirably as the liner is folded over the contents, but in any event it is folded inwardly before the cover is closed. The cover flap tongue 27 may be snapped through the slit 14 to retain the cover flap in closed position. With this arrangement the contents are effectively enclosed and the container may be handled without likelihood of the cover opening accidentally. The container complete with the liner may be shipped and stored in the knock-down or flat, quickly set up to receive the contents, and is readily closed.

I have illustrated and described my invention in a highly practical embodiment thereof. I have not attempted to illustrate or describe certain modifications or adaptations which I contemplate as it is believed this disclosure will enable those skilled in the art to practice the invention as may be desired.

Having thus described my invention what I claim as new and desire to secure by Letters Patent is:

1. In a lined container, the combination of bottom and body front, rear and end walls, the front and rear walls having corner flaps provided with upwardly directed tongues on their end edges, the front corner flaps having foldable extensions of substantial length on their upper edges, the front wall having a top flap on its upper edge, the end walls having slits opening at their end edges and extending diagonally outward from adjacent their bottom edges, the outer end portions of the slits being angularly disposed relative to their inner portions, said slits receiving the front and rear corner flaps with their tongue portions engaging the portions of the end walls above the slits, a cover extending from the top edge of the rear wall and having a closure flap on its swinging edge provided with a means detachably engageable with the front body wall, the cover having end flaps provided with front and rear projecting portions engageable through said slits in the said body end walls at the outer sides of the corner flaps, the front projecting portions having tongues engaging the portions of the end walls above the slits, the said several parts being formed of an integral blank scored to provide hinging connections therefor, and a liner sheet of a width corresponding substantially to the width of the blank and superimposed on the inner side thereof with one end substantially flush with the ends of the said front corner flap extensions, the other end terminating adjacent the swinging end of the cover, said liner being adhesively secured to the front wall and front corner flaps adjacent the upper edges thereof and to the rear wall and rear corner flaps adjacent the upper edges thereof and to the cover adjacent its swinging edge, whereby the liner is supported so that it is positioned within the container to line the parts thereof when the container is erected and closed.

2. In a lined container, the combination of bottom and body front, rear and end walls, the front and rear walls having corner flaps provided with upwardly directed tongues on their end edges, the front corner flaps having foldable extensions of substantial length on their upper edges, the front wall having a top flap on its upper edge, the end walls having slits opening

5 at their end edges and extending diagonally outward from adjacent their bottom edges, the outer end portions of the slits being angularly disposed relative to their inner portions, said slits receiving the front and rear corner flaps with their tongue portions engaging the portions of the end walls above the slits, a cover extending from the top edge of the rear wall and having a closure flap on its swinging edge provided with a means 10 detachably engageable with the front body wall, the cover having end flaps provided with front and rear projecting portions engageable through said slits in the said body end walls at the outer sides of the corner flaps, the front projecting portions having tongues engaging the portions of the end walls above the slits, the said several parts being formed of an integral blank scored to provide hinging connections therefor, and a liner sheet of a width corresponding substantially to the width of the blank and superimposed 15 on the inner side thereof with one end substantially flush with the ends of the said front corner flap extensions, the other end terminating adjacent the swinging end of the cover, said liner being secured to the blank to fold therewith when the container is erected.

3. In a container, the combination of bottom and body front, rear and end walls, the front and rear walls having corner flaps provided with upwardly directed tongues on their end edges, the front corner flaps having inwardly foldable extensions of substantial length on their upper edges, the front wall having a top flap on its upper edge, said front wall top flap being foldable inwardly in a direction at right angles to that in which the front corner flap foldable extensions are inwardly foldable, the end walls having slits opening at their end edges and extending diagonally outward from adjacent their bottom edges, the outer end portions of the slits being angularly disposed relative to their inner portions, said slits receiving the front and rear corner flaps with their tongue portions engaging the portions of the end walls above the slits, and a cover hingedly 20 connected to the top edge of the rear wall between said end walls and having a closure flap on its swinging edge provided with a means detachably engageable with the front body wall, the cover having end flaps provided with front and rear projecting portions engageable through said slits in the said body end walls at the outer sides of the corner flaps, the front projecting portions having tongues engaging the portions of the end walls above the slits, the said several parts being 25 formed of an integral blank scored to provide hinging connections therefor.

4. In a lined container, the combination of bottom and body front, rear and end walls, the front and rear walls having corner flaps provided with upwardly directed tongues on their end edges, the front corner flaps having foldable extensions of substantial length on their upper edges, the front wall having a top flap on its upper edge, the end walls having slits opening at their end edges and extending diagonally outward from adjacent their bottom edges, said slits receiving the front and rear corner flaps with their tongue portions engaging the portions of the end walls above the slits, a cover extending 30 from the top edge of the rear wall and having a closure flap on its swinging edge provided with a means detachably engageable with the front body wall, the cover having end flaps engageable through said slits in the said body end walls at the outer sides of the corner flaps, the said sev-

eral parts being formed of an integral blank scored to provide hinging connections therefor, and a liner sheet of a width corresponding substantially to the width of the blank and superimposed on the inner side thereof with one end substantially flush with the ends of the said front corner flap extensions, the other end terminating adjacent the swinging end of the cover, said liner sheet being adhesively secured to the front wall and front corner flaps adjacent the upper edges thereof and to the rear wall and rear corner flaps adjacent the upper edges thereof and to the cover adjacent its swinging edge, whereby the liner is supported so that it is positioned within the container to line the parts thereof when the container is erected and closed.

5. In a container, the combination of bottom and body front, rear and end walls, the front and rear walls having corner flaps provided with upwardly directed tongues on their end edges, the front corner flaps having inwardly foldable extensions of substantial length on their upper edges, the end walls having slits opening at their end edges and extending diagonally outward from adjacent their bottom edges, said slits receiving the front and rear corner flaps with their tongue portions engaging the portions of the end walls above the slits, and a cover hingedly connected to the top edge of the rear wall between said end walls and having a closure flap on its swinging edge provided with a means detachably engageable with the front body wall, the cover having end flaps engageable through said slits in the said body end walls at the outer sides of the corner flaps, the said several parts being formed of an integral blank scored to provide hinging connections therefor.

6. In a container, the combination of body bottom, front, rear and end walls, the front and rear walls having corner flaps provided with upwardly projecting tongues on their end edges, the end walls having slits opening at their end edges and extending diagonally upwardly from adjacent their bottom edges, said slits receiving the front and rear corner flaps with their tongue portions engaging the portions of the end walls

above the slits, and a cover hingedly connected to the top edge of the rear wall between said end walls and having front and rear portions projecting downwardly through said slits in said body end walls at the outer sides of the corner flaps.

7. In a container, the combination of bottom and body front, rear and end walls, the front and rear walls having corner flaps provided with upwardly directed tongues on their end edges, the front corner flaps having inwardly foldable extensions of substantial length on their upper edges, the end walls having slits opening at their end edges and extending diagonally outward from adjacent their bottom edges, said slits receiving the front and rear corner flaps with their tongue portions engaging the portions of the end walls above the slits, a cover hingedly connected to the top edge of the rear wall between said end walls, the cover having end flaps engageable through said slits in said body end walls at the outer sides of the corner flaps, said several parts being formed of an integral blank scored to provide hinging connections therefor.
